SWITCH FOR ELECTRIC PENCIL
SHARPENERSWilliam L. Rhodes, Jr., Aiken, S. C., assignor of
one-half to Thomas P. Mitchell, Aiken, S. C.

Application July 19, 1938, Serial No. 220,117

3 Claims. (Cl. 200—52)

The present invention relates to pencil sharpeners and has for its primary object to provide a switch operable upon contact by a pencil inserted in the sharpener to operate an electric motor for driving the sharpener.

A further object is to provide a switch mechanism of this character of simple and practical construction, which is neat and attractive in appearance, efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which—

Figure 1 is a side elevational view with parts broken away and shown in section.

Figure 2 is an end elevational view, and Figure 3 is a bottom plan view.

Referring now to the drawings in detail, wherein for the purpose of illustration I have disclosed a preferred embodiment of the invention, the numeral 5 denotes a base secured in spaced relation above a sub-base 6 by screws or the like 7. To the upper surface of the base 5 is secured a pair of spaced brackets 8 between which is mounted a pencil sharpener 9 of conventional construction.

The sharpener is arranged for operation by an electric motor 10 having a drive gear 11 operatively engaged with a pinion 12 mounted on the shaft 13 of the sharpener. Interposed in the circuit wires 14 leading to the motor is a toggle switch 15 having its operating lever 16 projecting downwardly through an opening in the base 5. The switch 15, motor 10 and gears 11 and 12 are enclosed in a suitable housing 17 secured to the upper surface of the base 5.

At the forward end of the sharpener is positioned a shaft 17 upon which is rotatably mounted a pair of spaced guide wheels 18 of conventional construction and having milled peripheries to facilitate gripping thereof and provided with a plurality of aligned pencil receiving openings 19 of various sizes to accommodate pencils of various diameters. Projecting forwardly from the bracket 8 is also a pin 20 upon which an upstanding arm 21 is pivotally mounted intermediate its ends, the upper end of the arm having a milled roller 22 secured thereto by a bolt 23, the axis of the roller being vertical and the roller being freely rotatable on the bolt 23.

As more clearly illustrated in Figure 2 of the drawings, one edge of the roller is positioned in partly overlying relation with respect to the pencil receiving opening 19 when the latter is positioned in alignment with the sharpener 9.

To the lower end of the arm 21 is pivotally secured one end of a rod 24 extending through a slotted opening 25 in the front edge of the base 5 and extending horizontally beneath the base with its other end provided with a yoke 26 engaging the lever 16 of the switch 15. The intermediate portion of the rod 24 is freely inserted in an opening 27 of a bracket 28 secured to the underside of the base 5, said bracket constituting a fulcrum point for the rod. Springs 29 and 30 are connected to the rod at opposite sides of the bracket and extend in opposite directions for attaching to the respective opposite sides of the base 5, to yieldably maintain the switch in its off position.

In the operation of the device as the pencil is inserted in the opening 19 the arm 21 will be actuated to close the switch through the connection thereof by means of the rod 24 in a manner as will be apparent. The free rotation of the roller 22 enables the pencil to be inserted and removed without binding against the arm 21.

It is believed the details of construction and manner of operation will be readily understood from the foregoing without further detailed explanation.

Having thus described the invention, what I claim is—

1. A switch operating mechanism for electrically operated pencil sharpeners comprising an upstanding arm pivotally mounted intermediate its ends, a pin projecting longitudinally from the upper end of the arm, a roller journaled on the pin and positioned in the path of a pencil when inserted in the sharpener for pivotally actuating the arm, and a horizontally extending switch operating rod secured to the lower end of said arm for closing a switch upon insertion of a pencil in the sharpener, and spring means yieldably urging the rod into a position for opening the switch.

2. A switch operating mechanism for electrically operated pencil sharpeners comprising a vertically positioned arm pivotally mounted intermediate its ends, a pin projecting longitudinally from the upper end of the arm, a roller journaled on the pin and positioned in the path of a pencil when inserted in the sharpener for pivotally actuating the arm, a horizontally extending rod pivoted intermediate its ends and

having one end secured to the lower end of said arm, a switch including a lever, a yoke engaging the lever at the opposite end of the rod and adapted for moving the lever into a switch closing position upon the actuation of the arm and spring means yieldably urging the rod into a position for opening the switch.

5. A switch operating mechanism for an electric pencil sharpener, said sharpener and switch being mounted on a supporting base, said mechanism comprising an upstanding arm pivotally

mounted intermediate its ends to the sharpener with the upper end of the arm in the path of a pencil inserted into the sharpener for actuating the arm and a rod pivoted intermediate its ends beneath the base, one end of the rod being connected to the switch and the other end of the rod being connected to the lower end of the arm for transmitting actuating movement of the arm to the switch.
